DISH COVER

Filed Oct. 17, 1927

Inventor
John B. Zallio
By Robert F. Michle, Jr.
Attorney

UNITED STATES PATENT OFFICE

JOHN B. ZALLIO, OF CHICAGO, ILLINOIS

DISH COVER

Application filed October 17, 1927. Serial No. 226,590.

My invention has for its general objects the provision of a dish cover which is adapted to permit the stacking of food laden dishes with comparative safety and which retards the transmission of heat between the stacked dishes, so that the food on the dishes will remain hot or cold as the case may be for a comparatively long period with obvious advantage particularly in restaurant service where some time generally elapses between the placing of the food on the service plates and the serving of the patrons therewith.

With these objects in view my invention consists in certain features of novelty in the construction, combination, and arrangement of parts by which the said objects and certain other objects, hereinafter appearing, are effected, all as fully described with reference to the accompanying drawing and more particularly pointed out in the appended claims.

20 In the said drawing—

Figure 1 is bottom plan view of a dish cover embodying my invention;

Figure 2 is a section thereof on the line 25 2—2 of Figure 1.

Like characters of reference indicate like parts in the several views.

Referring to the drawing, 1 designates a cup shaped annular body, preferably formed of suitable sheet metal such as aluminum. The transverse wall of the body is provided with an annular flange or margin portion 2 which is substantially frusto-conical and projects inwardly and in the direction of the other end of the body. The center portion of the transverse wall of the body, designated at 3, is offset from the margin portion 2 in the direction of the other end of the body and is connected with the margin portion 2 by means of an annular connecting portion 4 which is inwardly undercut to form a convenient finger hold for the lifting of the cover.

The body 1 is provided with an annular flange 5 at and surrounding the axial opening thereof and this flange projects radially outwardly from this opening and corresponding with the plane thereof. A second annular flange 6 formed on the flange 5 at the outer edge thereof surrounds the opening of

the body in spaced relation therewith and projects from the flange 5 in a direction outwardly from said opening.

The flange 5, between the opening of the body and the flange 6, and the margin 2 are provided with apertures 7 spaced therearound, and engaged in said apertures are circumferentially grooved rubber bushings 8.

The bushings 8 on the margin portion 2 project exteriorly thereof for engagement with the under surface of the substantially frusto-conical margin portion of a service plate 9, see Figure 2, to support this plate above the body 1 in spaced relation therewith, the margin portion 2 and the center 60 portion 3 of the transverse wall of the body corresponding roughly with the form of the corresponding portion of the under surface of the plate for this purpose and to prevent lateral displacement of this plate.

The bushings 8 on the flange 5 project downwardly therefrom and correspondingly with the projection of the flange 6 for engagement with the margin portion of the upper surface of a second service plate 10, see Figure 2, to support the body 1 above this plate in spaced relation therewith for enclosing food on this plate, the flange 6 surrounding the outer edge of this plate to prevent displacement of the cover and obstructing direct communication through the space between the flange 5 and this plate.

The bushings 8 provide support means of restricted area adapted for engagement with the service plates whereby the plates are 85 maintained in spaced relation with the body and its parts whereby the transmission of heat is effectively retarded.

In Figure 2 but two service plates are shown in stacked relation with one dish cover, 90 it being apparent that any reasonable number of service plates covered with dish covers of my invention may be stacked with reasonable safety.

While I have herein shown and particularly described the preferred embodiment of my invention I do not wish to be limited to the precise details of construction shown as changes may readily be made without departing from the spirit of my invention, but 100

having thus described my invention I claim as new and desire to secure by Letters Patent the following:—

1. In an article of the character described the combination in a cup shaped body, of an annular substantially frusto-conical margin portion of the transverse wall of the body projecting inwardly and in the direction of the other end of the same, the center portion of said transverse wall being offset from said margin portion in the direction of the other end of the body, and an inwardly undercut annular connecting portion between said margin and center portions of said transverse wall.

2. In an article of the character described the combination with a cup shaped metal body, of an annular substantially frusto-conical margin portion of the transverse wall of the body projecting inwardly and in the direction of the other end of the same and provided with apertures spaced therearound, the center portion of said transverse wall being offset from said margin portion in the direction of the other end of the body, an inwardly undercut annular connecting portion between said margin and center portions of said transverse wall, and circumferentially grooved rubber bushings engaged in said apertures and projecting exteriorly of said margin portion.

3. In an article of the character described the combination with a hollow metal body provided with an opening, of a flange on the body surrounding said opening and projecting outwardly therefrom in a direction corresponding with the plane of said opening, a second flange on said first mentioned flange and surrounding said opening in outwardly spaced relation therewith and projecting from said first mentioned flange in a direction outwardly from said opening, said first mentioned flange being provided with apertures spaced therearound and disposed between said opening and said second flange, and rubber support members secured in said apertures and projecting from said first mentioned flange correspondingly with said projection of said second flange.

4. In an article of the character described the combination with an annular hollow metal body provided with an axial opening, of an annular flange on the body at and surrounding said opening and projecting radially outwardly therefrom, a second annular flange on said first mentioned flange at the outer edge thereof and projecting axially therefrom in a direction outwardly from said opening, said first mentioned flange being provided with apertures spaced therearound and disposed between said opening and said second flange, and circumferentially grooved rubber bushings engaged in said apertures and projecting from said first mentioned

flange correspondingly with said projection of said second flange.

In witness whereof I hereunto affix my signature this tenth day of October, 1927.

JOHN B. ZALLIO.
